UNITED STATES PATENT OFFICE.

FRANKLIN CHATFIELD, OF MINNEAPOLIS, MINNESOTA, ASSIGNOR TO NORTHWESTERN
KNITTING COMPANY, OF MINNEAPOLIS, MINNESOTA, A CORPORATION.

LADY'S UNDERGARMENT.

1,211,917.

Specification of Letters Patent.

Patented Jan. 9, 1917.

Application filed September 21, 1915. Serial No. 51,869.

To all whom it may concern:

Be it known that I, FRANKLIN CHATFIELD, citizen of the United States, resident of Minneapolis, county of Hennepin, State of Minnesota, have invented certain new and useful Improvements in Ladies' Undergarments, of which the following is a specification.

The object of my invention is to provide an undergarment having a closed crotch and leg and hip portions which may be drawn to one side to provide a posterior opening without having the objectionable fullness incidental to garments of this kind as usually made.

Other objects of the invention will appear from the following detailed description.

In the accompanying drawings forming part of this specification, Figure 1 is a front view of a lady's undergarment embodying my invention, Fig. 2 is a side view of the same, Fig. 3 is a side view, showing the initial movement for opening the garment to provide a posterior opening, Fig. 4 is a rear view, showing the further side movement of the garment, Fig. 5 is a rear view of the garment, with the posterior opening fully exposed.

In the drawing, 2 represents the upper or bust portion of the garment, which may be made in any suitable way, with the inserts 3 under the arms or not, as preferred.

4 represents the closed crotch portion of the garment and 5 the hip portions and 6 the leg portions, which, as shown in Fig. 1, extend preferably a short distance below the closed crotch. The leg portions may be made longer than as shown, if preferred. These hip and leg portions in a garment of this kind as usually made are loose to provide sufficient fullness for a seat opening and are objectionable because of this additional fullness around the body at this point.

To obviate this objection and still provide for the posterior opening, I arrange gore inserts 7 and 8 in the leg and hip portions, extending up into the body portion of the garment above the hips, approximately to the waist line. These gore inserts are stitched at 9 and 10 to the leg and hip portions of the garment and overlap one another. The upper edge of the gore 7 is stitched at 11 to the hip portion of the garment coinciding with the seam 9 and the corresponding edge of the gore 8 is stitched to the other side and

coincides with the seam 10 and is concealed by the gore 7. The lower portions of these gores are loose on one side and lap by one another, either one on the outside, sufficiently to close the opening between them, the loose edges having freedom of separation, as indicated in Fig. 3, sufficient to allow the leg portion to be separated and drawn to one side, as indicated in Fig. 4, and as the wearer assumes the sitting position shown in Fig. 5, the side or lateral movement of the rear of the garment may be continued until the posterior opening is fully exposed. Normally, the garment will hang on the person substantially as shown in Figs. 1 and 2, the leg portions being sufficiently loose to allow freedom of movement without being bulky or cumbersome and without bunching around the legs or hips of the wearer. I have shown both sides of the garment equipped with these gore inserts so that the leg portions on either side may be opened, though of course only one side of the garment may have the inserts therein, but I prefer the openings on both sides, as shown.

The width and length of the gore inserts may, of course, be modified and the length of the gap between the inserts may be changed, and in various ways the details of the garment may be altered and still be within the scope of my invention.

I claim as my invention:

1. A lady's undergarment comprising an upper portion and leg portions having a closed crotch between them, overlapping gore inserts having their edges stitched to said leg portions, the lower edges of said inserts on one side having loose edges lapping by one another and allowing said leg portions to be drawn to one side to provide a posterior opening.

2. A lady's undergarment comprising a bust and body portion and leg portions having a closed crotch between them, gore inserts fitting into said leg portions over the hips of the garment and extending upwardly therein to a point adjacent the waist line, the upper portions of said gore inserts being stitched on both sides to the garment, said gore inserts lapping by one another and the lower portions thereof being stitched on one side only to the garment, the opposite edges thereof being loose and having freedom of separation to allow the leg

2
portion of the garment to be drawn to one side to provide a posterior opening.

3. A lady's undergarment comprising an upper portion and leg portions having a closed crotch between them, gore inserts stitched on one edge to a leg portion, the other contiguous edges of said inserts being

loose and providing an opening running lengthwise of the leg portion for allowing it to be drawn to one side to provide a posterior opening.

In witness whereof, I have hereunto set my hand this 17th day of September 1915.

FRANKLIN CHATFIELD.
